Primary Examiner — Sheryl Lane(74) *Attorney, Agent, or Firm* — McGuireWoods LLP**CLAIM**

I claim the ornamental design for a battery powered hedge trimmer, as shown and described.

DESCRIPTION

FIG. 1 is a right perspective view of the battery powered hedge trimmer;

FIG. 2 is a front view of the battery powered hedge trimmer shown in FIG. 1;

FIG. 3 is a rear view of the battery powered hedge trimmer shown in FIG. 1;

FIG. 4 is a left view of the battery powered hedge trimmer shown in FIG. 1;

FIG. 5 is a right view of the battery powered hedge trimmer shown in FIG. 1;

FIG. 6 is a top view of the battery powered hedge trimmer shown in FIG. 1; and,

FIG. 7 is a bottom view of the battery powered hedge trimmer shown in FIG. 1.

The broken lines represent portions of the article and form no part of the claimed design.

1 Claim, 4 Drawing Sheets---
